UNITED STATES PATENT OFFICE.

MAHLON J. RENTSCHLER, OF WILLOUGHBY, OHIO, ASSIGNOR OF ONE-HALF TO WILLIAM R. JEAVONS, OF CLEVELAND HEIGHTS, OHIO.

WASHING POWDER.

No Drawing.

Application filed May 29, 1922. Serial No. 564,568.

This invention is a novel washing powder intended for use in connection with either hot or cold water for the purpose of washing clothes, dishes and other articles. The 5 object of the invention is to provide a simple and inexpensive compound, one which is easily fabricated and packaged and one which, when used, will be readily dissolved, producing an abundant quantity of suds and 10 at the same time softening the water, cutting the grease and dissolving and lixiviating the dirt. Another object of the invention is to provide a compound embodying these advantageous characteristics which 15 will be the least harmful to the hands and also the fabrics or cloths being cleansed.

With these various objects in view my invention consists broadly in providing a 20 washing powder comprising neutral tallow soap, tri sodium phosphate, sal soda and bicarbonate of soda and Glauber's salt.

The invention consists also in certain 25 details hereinafter fully described and set forth in the appended claim.

In compounding a washing powder in accordance with my invention I employ substantially twenty parts by weight of neutral tallow soap which constitutes the soapy base 30 of the compound. I also employ substantially twenty parts by weight of tri sodium phosphate, this ingredient serving to soften the water without precipitation and also serving as a detergent and grease solvent.

I use about forty parts by weight of soda, 35 that is a mixture of substantially equal parts of sal soda and bicarbonate of soda. This soda aiding the compound both as a detergent and as a grease solvent.

In combination with the preceding ingredients I employ about twenty parts by 40 weight of Glauber's salt which has a remarkable action as a dirt solvent and particularly as bringing about the action of lixiviation,

inasmuch as the dirt and grease are readily separated from the fibrous or cellular portions of the cloths or fabrics and brought to the surface where they are immediately dissolved and removed. 45

While I have specified the various ingredients in the proportions specified it will, 50 of course, be understood that there may be variations in either direction so long as the general proportions are retained, that is, I prefer to employ substantially equal parts of the neutral tallow soap, tri sodium phosphate and Glauber's salt and about double 55 the quantity of soda.

These proportions I have found to combine excellently to provide a washing powder which readily dissolves, producing an 60 abundance of suds immediately and through the medium of the various ingredients any and all kinds of water is softened, the grease is cut, and all varieties of dirt are dissolved and lixiviated. 65

In compounding the powder, the ingredients, in substantially the proportions set forth, are ground into a fine powder, and this powder I prefer to treat with a limited amount of moisture either in the form of 70 steam or water so that the powder is transformed to a somewhat cementitious condition. This compound thus moistened may then be repulverized if desired and is then ready for packing. 75

Having thus described my invention, what I claim is:

A washing powder comprising:	Parts by weight.
Neutral tallow soap	20
Tri sodium phosphate	20
Sal soda	20
Bicarbonate soda	20
Glauber's salt	20

In testimony whereof, I hereunto affix my signature.

MAHLON J. RENTSCHLER.
